FISHING STAND

Alvin L. Stout, San Antonio, Tex., assignor to
Ellis M. Wilson, San Antonio, Tex.

Filed June 24, 1974, Ser. No. 482,248

Term of patent 14 years

Int. Cl. D22—05

U.S. Cl. D22—13

FIG. 1

FIG. 2FIG. 3

FIG. 1 is an environmental view depicting a fishing stand, the broken lines being for illustrative purposes only;

FIG. 2 is a front elevation view; and

FIG. 3 is a left side view.

The front and back of the invention are identical and the left side and right side are identical.

I claim:

The ornamental design for a fishing stand, as shown and described.
